Primary Examiner — Marie D. Fast Horse

(74) *Attorney, Agent, or Firm* — CANTOR COLBURN LLP

(57) **CLAIM**

The ornamental design for a payment POS machine, as shown and described.

DESCRIPTION

FIG. 1 is a bottom, front, right side perspective view of a payment POS machine showing our new design;

FIG. 2 is a top, rear, left side perspective view thereof;

FIG. 3 is a front elevation view thereof;

FIG. 4 is a rear side elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged figure of a part of FIG. 2.

The broken lines in the drawings depict portions of the payment POS machine that form no part of the claimed design.

1 Claim, 9 Drawing Sheets

FIG. 9
